UNITED STATES PATENT OFFICE.

EDWARD H. ANDERSON, OF SCHENECTADY, NEW YORK, ASSIGNOR TO GENERAL ELECTRIC COMPANY, A CORPORATION OF NEW YORK.

ELECTRIC BRAKE.

No. 895,830.

Specification of Letters Patent.

Patented Aug. 11, 1908.

Application filed July 23, 1901. Serial No. 69,417.

To all whom it may concern:

Be it known that I, EDWARD H. ANDERSON, a citizen of the United States, residing at Schenectady, county of Schenectady, 5 State of New York, have invented certain new and useful Improvements in Electric Brakes, of which the following is a specification.

This invention relates to electric-railway 10 brakes, and its object is to cause the brake-chain of an ordinary brake-rigging to be wound up by electric power whenever the motorman turns the brake-handle in the usual manner of putting on the brakes.

15 Many of the modern trolley-cars are 35 or 40 feet long and correspondingly heavy. The work involved in stopping such a car by the ordinary hand-brakes is very severe on the motorman. My invention aims to 20 replace hand brakes by providing the brake-rigging with a small electric motor, controlled by the customary motion of the brake-handle, and operating to wind up the chain when the handle is revolved, thus 25 relieving the motorman of all work other than merely overcoming the friction of the handle and its staff or spindle.

The preferred mode of carrying my invention into effect is shown in the accompanying 30 drawings, in which

Figure 1 is a sectional elevation of my improved brake-operating mechanism; Fig. 2 is a plan view on the line 2—2, Fig. 1; Fig. 3 is a plan view on the line 3—3, Fig. 1; Fig. 4 35 is a diagram of the circuits; Fig. 5 is a diagram of a modification.

The brake-chain A is attached as usual to an upright rotatable staff or spindle B extending up through the floor C at the end of 40 the car or the car platform, and provided with a tubular portion B¹ rotatably sleeved or loosely mounted on the portion B. To the upper end of the portion B¹ the handle D is attached. A screw E passing through the 45 tubular portion B¹ into a groove b in the staff B keeps the two parts together. To the tubular portion B¹ just above the floor C is secured the usual ratchet-wheel F engaged by the detent-pawl f. The portion B¹ extends 50 below the floor, where one portion of the staff carries a dog G having a tail g lying between the lugs h on a notched sector H secured to the other portion of the staff, there being sufficient space between the lugs

to give a certain amount of play to the dog. 55 From this construction it will be seen that the customary revolution of the handle D will carry the dog into contact with a lug on the sector and connect the two parts of the brake-staff so that they rotate together in 60 the usual manner. But in order to relieve the motorman of the labor involved in thus applying the brakes by hand, I connect the brake-rigging with the armature of an electric motor, and locate a plurality of field-coils adjacent thereto, preferably arranged to be progressively energized by current from the trolley or other source of power, so as to set up a rotating field and cause the armature to rotate and apply the brakes. 65 The field coils are shown in the accompanying drawings as connected to a commutator on which runs a brush carried by the tubular portion B¹ of the staff but it will be understood that other means may be employed 70 whereby the motor is controlled from the operating handle.

The field-coils I are shown as twelve in number, though any multiple of the armature-poles may be used. The twelve field-coils K project inwardly from an annular frame k concentric with the staff B and attached to the floor C by hangers K¹. The flat field-coils I each include three cores, each coil being offset twice to enable succeeding 85 coils to overlap. The coils are connected in multiple to a lead 1 from the trolley, a suitable permanent resistance L being included in the circuit to cut down the current to the proper amount. The other terminal of each 90 coil is connected with a segment m of a fixed commutator M supported concentric with the staff B, preferably by a ring m¹ resting on top of the frame k. The twelve segments of the commutator are connected by leads 3 95 into three groups of four each, spaced at equal distances around the staff. Resting on the commutator is a brush N carried by, but insulated from, the portion B¹ of the staff, and connected with the coils P on the armature P¹ which is secured to the staff B inside the field-coils. The four armature-coils are all in series and one terminal is grounded through the shaft B. The armature is preferably mounted on the shaft or spindle B so 100 that the said shaft extends on both sides of said armature, the upper extending end carrying the brake handle and the lower extend-

ing end being equipped with the brake-chain which is wound and unwound for applying and releasing the brake. A casing R covers the working parts.

- 3 The operation of the preferred modification of my invention is as follows: When the switch S is closed, current flows through the trolley-lead 1 to the four equi-distant field-coils I connected with that segment of the commutator on which the brush rests, passing through said brush and the armature-coils to ground. The four energized field-coils produce two pairs of resultant magnetic poles lying at right angles. The 10 pole-pieces of the armature are magnetized similarly and at once rotate enough to place themselves in correspondence with those of the field. If the motorman now revolves the handle D, carrying the brush to the next commutator-segment, the current is 15 cut off from the first set of field-coils and energizes the next set, thereby shifting the resultant poles one-twelfth of a revolution. The armature at once turns to place itself in line with the new position of the field-poles and this operation is repeated every time the brush moves on to a new segment either in 20 forward or backward direction of movement. It thus appears that the simple turning of the 25 handle D causes the resultant field-poles to rotate, exerting a torque on the armature and thereby winding up or releasing the 30 brake-chain depending upon the direction of rotation of the handle. The play of the dog 35 between the lugs h is sufficient to permit the brush to pass from one segment to another before the dog strikes the leading lug, so that provided the torque produced by the motor 40 is sufficiently great this lug is always kept in advance of the dog in either direction of rotation of the spindle, and the work of the motorman is reduced to merely overcoming the 45 friction of the tubular portion B¹ of the staff. If the motor stops for any reason, such as 50 lack of current, the slight backward movement of the armature brings the leading lug h against the dog, and the motorman can then continue the application of the brakes in the usual manner.

- 55 In the modification shown in Fig. 5, only one motor is used, but two commutators are provided, one for each brake-handle, and connected in multiple, so that the operation of either handle will cause the armature of the motor to rotate.

To simplify the wiring of the car, the field coils are connected by leads 4 into three groups of four each, and each group is connected by a lead 5 with one of the three 60 groups of connected segments on each commutator. The tubular portion of the brake-staff is omitted, the handle and brush being carried on the staff B. A switch S¹ is provided in each lead 6, which connects each 65 brush with one terminal of the armature-

coils, the other terminal of said coils being grounded through the motor-shaft T. By means of the switches S¹, the rear commutator can be cut out, leaving the brake-motor wholly under control of the handle at that 70 end of the car which, for the time being, is the front end.

In Fig. 5 the right-hand commutator is in use, and the brush is supposed just to have been moved to the position shown, causing 75 current to flow through the field-coils lettered I and the segments lettered m. The armature is about to rotate clockwise to place its coils P in line with the coils I.

The brake-rigging comprises the customary brake-beams U, connected by pull-rods u with the lever U¹, which is connected by rods and chains u¹ with the brake-staffs. An additional brake-chain V connects the lever U¹ with the shaft of the motor T, which is 80 placed under the body of the car near said lever. The rotation of the brake-staff B not only sets the motor running to wind up the chain V, but it also winds up the slack of the chain u¹, so that when the motor stops for 85 lack of current, the application of the brakes is continued by the further rotation of the 90 brake-staff winding up the chain u¹.

While I have illustrated and described my 95 invention as applied to a brake-rigging and have hereinafter claimed it in combination with said brake-rigging, it will of course be understood that it is not so limited in its application as it may be advantageously employed to control the movements of other 100 power-operated shafts or members, and I aim in the appended claims to cover all modifications of my invention which do not involve a departure from its spirit and scope.

What I claim as new and desire to secure 105 by Letters Patent of the United States, is,

1. The combination with the brake-rigging of an electric railway car, of an electric motor arranged to actuate said rigging, a commutator for said motor concentric with 110 the brake-staff, and a brush carried by said staff.

2. The combination with a brake-rigging, of an electric motor arranged to wind up the chain of said rigging, means for causing said 115 motor to rotate by the turning of the brake-handle, and to keep slightly in advance of said handle.

3. The combination with a brake-rigging, of an electric motor arranged to wind up the 120 chain of said rigging, means for causing said motor to rotate by the turning of the brake-handle, and to keep slightly in advance of said handle, and means whereby said handle can continue the application of the brake in 125 case the motor stops.

4. The combination with a rotatable member, of a motor having an armature and a multipolar field-magnet concentric therewith, a commutator connected with the field- 130

coils, and a brush making contact with said commutator and actuated by the member.

5. The combination with a motor having a multipolar field-magnet composed of coils connected in parallel, of a commutator having a segment for each coil, independent leads connecting equidistant segments into groups, an armature concentric with said field-magnet, a brush making contact with one segment at a time and in series with the armature, and means for moving the brush.

6. The combination with the brake-rigging of an electric car, of a brake-staff and handle, a rotatable armature for actuating said brake-staff, and means controlled by the movement of said handle for producing a rotating field of force for exerting a torque on said armature, said field of force having an angular velocity corresponding to that of the brake-handle.

7. The combination with the brake-rigging of an electric car, of a rotatable armature for actuating said rigging, and means whereby the revolution of the brake-handle produces a rotating field of force to exert a torque on said armature.

8. The combination with the brake-rigging of an electric car, of a motor comprising an armature connected with said rigging, a multipolar field - magnet having overlapping coils, and means for energizing one or more pairs of opposite coils in regular progression.

9. The combination with the brake-rigging of an electric car, of a motor having an armature connected with said rigging, a multipolar field - magnet having overlapping coils, and means actuated by a brake-staff for energizing one or more pairs of opposite coils in regular progression.

40 10. The combination with the brake-rigging of an electric car, of a motor having an armature connected with said rigging, a multipolar field-magnet having overlapping offset flat coils each including more than one pole-piece and connected in multiple, a commutator having a segment for each coil, and a brush on the brake-staff making contact with said commutator.

11. In a brake-system, a brake-staff made 50 in two relatively rotatable portions, and means for connecting said portions with a certain amount of lost motion, whereby the handle may be moved a certain distance in either direction without moving the brake staff, but a further movement of the handle will cause the staff to move in a direction corresponding to the direction of movement of the handle.

12. In a brake-system, a brake-staff comprising two portions, one sleeved on the other, a notched sector on one portion, and a dog on the other portion engaging said sector, whereby one portion of said brake staff may be moved to a certain degree in either direction without moving the other portion of said

staff, but a further movement of the first-mentioned portion will cause the second-mentioned portion to move in a direction corresponding to the direction of movement of the said first-mentioned portion.

70

13. In combination, a braking device, a rotary motor for actuating said device, a brake-handle, and means separate from said handle but controlled thereby for causing the motor to rotate through an angular distance corresponding to the movement of the handle.

75

14. In combination, a braking device, a rotary motor for actuating said device, a brake handle, means operated when said handle is moved for controlling the energization of said motor to cause it to rotate through an angular distance corresponding to the movement of the handle, and a mechanical connection between the said braking device and said handle.

85

15. In combination, a braking device, a rotary motor for actuating said device, a brake-handle, means comprising a commutator connected with said motor and a brush operated by said handle for controlling the angular movement of said motor, and a mechanical connection between the braking device and the handle.

90

16. In combination, a braking device, a motor for actuating said device, a brake-handle, a brake-staff, a lost motion device connecting said staff to said handle, means operated by said handle for controlling the movement of the motor, and a mechanical connection between the braking device and the brake-staff.

95

17. In combination, a braking device, a motor for actuating said device, a brake-handle, means operated by said handle for controlling the movement of the motor, and a mechanical connection having a lost motion between the braking device and the brake-handle.

105

18. The combination with a rotatable member, of an armature carried by said member, a multipolar field magnet, a commutator connected with the field coils, an operating handle, and a brush making contact with the commutator and actuated by said handle, whereby the field coils are successively connected in circuit to cause said member to rotate.

110

19. The combination with a rotatable member, of an armature carried by said member, a multipolar field magnet, a commutator connected with the field coils, an operating handle, a brush making contact with the commutator and actuated by said handle, whereby the field coils are successively connected in circuit to cause said member to rotate, and independent means whereby said member may be rotated by said handle.

120

20. In an apparatus of the character described, a power driven brake spindle, an electric motor for operating said spindle, and

125

130

a handle mounted on said spindle and having a lost motion connection therewith arranged to control said motor.

21. The combination with a rotatable member, of a motor connected to rotate said member, a handle loosely mounted on said member, and means operated by said handle for controlling the operation of said motor.

22. The combination with a rotatable member, of a motor connected to rotate said member, a handle loosely mounted on said member, means operated by said handle for controlling the operation of said motor, and means whereby said member may be mechanically operated by said handle.

23. In an apparatus of the character described, a power driven brake spindle, a mo-

tor for operating said spindle, a loose handle for said spindle, and means for controlling the said motor from said handle.

24. In combination a rotatable member, an electric motor arranged to rotate said member, a handle mounted on said member and having a lost motion connection therewith, a chain which is wound around said member as the latter is rotated, and means for controlling said motor from said handle.

In witness whereof I have hereunto set my hand this 19th day of July, 1901.

EDWARD H. ANDERSON.
